APPARATUS FOR VISUAL DETECTION OF
SUSPENDED MATTER IN FLUIDWilliam T. Fleming, West Orange, N. J., assignor
to Specialties Development Corporation, Belle-
ville, N. J., a corporation of New Jersey

Application December 27, 1950, Serial No. 202,977

6 Claims. (Cl. 88—14)

1

The present invention relates to apparatus for visually detecting suspended matter in fluid, and, more particularly, to improvements in smoke detectors primarily adapted for use on aircraft or other craft or vehicles where the space for such apparatus on the instrument panel is extremely limited.

Heretofore, visual smoke detectors have been utilized to supervise one or several compartments or zones in which smoke may occur by continuously withdrawing samples of the air from such zones or compartments and passing a stream of air withdrawn through a beam of light to illuminate smoke particles suspended in the stream whereby the presence of smoke may be observed visually in the stream. In connection with such smoke detectors, it has been found that the illuminated particles can be seen more readily when looking in the direction toward the light source but obliquely thereto.

Accordingly, an object of the present invention is to provide such a visual smoke detector or the like which is extremely small in size and compact in arrangement and which takes advantage of the foregoing phenomenon, whereby smoke is readily detected.

Another object is to provide such a smoke detector wherein stray light which might hinder the observer is reduced to a minimum.

Another object is to provide such a smoke detector wherein provision is made for readily determining whether or not the beam of light for illuminating the air stream is being directed through the stream.

A further object is to provide means for selectively rendering the light beam determining means just mentioned effective and ineffective.

Other and further objects of the invention will be obvious upon an understanding of the illustrative embodiment about to be described, or will be indicated in the appended claims, and various advantages not referred to herein will occur to one skilled in the art upon employment of the invention in practice.

In accordance with the present invention, the foregoing objects are generally accomplished by providing apparatus comprising in combination a casing having a sight opening including a window, a light source for providing a beam of light, means for directing the beam in the general direction of the opening but along one side of the window whereby the beam will be viewed obliquely through the window when looking therethrough, and means for conducting a stream of fluid into the light beam.

In a preferred embodiment of the invention

2

about to be described, the air stream and the light beam are directed through a common aperture in a partition positioned within the casing, a shield is positioned between the window and this partition, but to one side of the light beam, and translucent means adapted to be illuminated by the beam are positioned adjacent the window directly in the path of the beam. The translucent means serves as a pilot light adapted to indicate whether or not the light source is functioning. The pilot light may be rendered effective and ineffective at will by a shutter disposed between these means and the light source, which shutter is operable from the exterior of the casing. The air, in which smoke is to be detected, preferably, is introduced into the casing between the partition and the end wall of the casing having the window therein, and is withdrawn from the casing at the opposite end thereof.

20 A preferred embodiment of the invention has been chosen for purposes of illustration and description, and is shown in the accompanying drawing, forming a part of the specification, wherein:

25 Figure 1 is a front elevational view of a smoke detecting device in accordance with the invention.

Figure 2 is a sectional view taken along the line 2—2 on Figure 1, illustrating the interior of the device.

Figure 3 is a fragmentary sectional view taken along the line 3—3 on Figure 2, illustrating the shutter for controlling the pilot light.

Referring to the drawing in detail, there is shown a smoke detecting device generally comprising a casing 10, a light source for providing a beam of light, such as a lamp 11, and conduit means for passing an air stream through the light beam.

40 The casing 10 is generally rectangular, and has a front wall 12, a rear wall 13, a top wall 14, a bottom wall 15, and side walls 16. These walls may be so dimensioned to provide a casing which is small and compact to facilitate mounting the same on an instrument or control panel of a craft or vehicle with the front wall 12 being substantially flush with the panel. In practice, it has been found feasible to utilize a casing which occupies less than thirty cubic inches of space.

45 The front wall 12 has a rectangular sight opening 17 in the upper portion thereof, a transparent window 18 extending inwardly into the casing from the lower edge of the opening and a translucent button or disc 19 just below the opening, the purpose of which will be made apparent hereinafter.

50 55 A partition 20 is positioned in the casing be-

tween the front and rear walls thereof which preferably extends from the top to the bottom walls and from one side wall to the other, whereby the casing is divided into forward and rearward zones. The partition, as shown, has a lower vertical section 21 on which the lamp 11 is mounted at the side within the rearward casing zone, and has an upper, downwardly and rearwardly inclined section 22 formed with an aperture 23 which is in horizontal alignment with the opening 17.

The conduit means for circulating an air stream through the casing in which smoke is to be detected comprise a tube 24 extending through the rear wall 13 and the partition 20 to the forward casing zone, and an opening in the rear wall having a tube 25 in communication therewith. Preferably, the air is introduced through the tube 24 into the forward zone, is passed through the aperture 23 in partition 22 to the rearward zone, and is removed from the rearward zone through the tube 25.

The air stream in being so circulated passes through a beam of light adapted to illuminate smoke particles suspended in the stream. This light beam is provided by the lamp 11 and is directed through the partition aperture 23 by a reflector 26 mounted on the top wall 14 in the rearward zone. The reflector is so positioned that the light beam is directed substantially directly towards the opening 17 but just below the lower side edge thereof whereby the center of the beam is directed on the center of the button 19. In this manner, the light beam and air stream intersect each other, and the button is illuminated when the lamp is functioning to thereby serve as a pilot light. Preferably, a lens 27 is positioned between the lamp and the reflector to condense the light beam.

Stray light in the forward casing zone is reduced by blackening the interior wall surfaces, and stray light is prevented from being viewed when looking through the opening by positioning one or more baffles adjacent the light beam and between the opening 17 and the partition aperture 23 through which the beam is directed (Figure 2). For example, as shown, two baffles 28 and 29 are provided which extend from one side wall to the other side wall of the casing. These baffles depend from the top wall of the casing and are inclined downwardly and rearwardly substantially at the same angle as the partition whereby they are parallel thereto. The baffle 28 nearest the opening is longer than the baffle 29 and its lower edge is nearer to the center of the beam than that of the baffle 29. By being so arranged, the shorter baffle 29 blocks the light diffused upwardly at a wide angle and the longer baffle 28 blocks the stray light of the upper part of the beam which gets past the shorter baffle.

As shown herein, the inner edge of the window 18 is supported by suitable means adjacent the lower edge of the baffle 28, and is positioned substantially parallel to the light beam to minimize the reflection of stray light thereon from the interior of the casing. The forward end of the top wall 14 shields the window against reflection of stray light at the exterior of the casing.

When the interior of the casing is observed by looking through opening 17 and the window 18, as indicated by the arrow A (Figure 2), the baffle 28 obscures the aperture 23. The line of vision thus is in general direction towards the origin of the beam but is oblique thereto whereby any illuminated smoke particles can be readily seen.

This is accomplished with an extremely small and compact device by arranging the apertured partition, the baffles, the opening and the window as shown.

5 While the provision of a pilot light is a desirable feature, it is also desirable that the instrument panel, particularly near the smoke detecting observation window, be kept as dark as possible. Hence, it is contemplated that the pilot light should be visible only when it is desired to determine whether or not the lamp is in working order, and should be darkened at all other times. This is accomplished in a convenient manner by placing a movable shutter between the light beam and the button 19.

As shown in Figures 2 and 3, a shutter 30 in the form of a segment of a circular disc is mounted on and is secured to a shaft 31 which is rotatably supported in a bushing 32 and extends outwardly through the front wall of the casing. The shutter has a slot 34 at one side thereof which permits the light beam to pass therethrough and be directed on the translucent button. The other side 35 of the shutter is impervious to light and serves to prevent the beam from reaching the button. Stray light is prevented from getting around the shutter by a housing 36 enclosing the shutter and the portion of the button at the interior of the front wall. This housing has an aperture 37 in line with the button 19 to permit the central portion of the light beam to pass therethrough.

35 The shutter, as shown herein, is in its central or neutral position, but is adapted to be moved to the right to allow the beam to strike the button, or to the left to block the beam and darken the button. A handle 39 is provided on the shaft 31 at the exterior of the casing for effecting movement of the shutter, and cooperating indicia are provided on the front wall of the casing (Figure 1) to indicate the on and off pilot light positions of the shutter.

40 From the foregoing description, it will be seen that the present invention provides a simple, practical and economical visual smoke detecting device which is small and compact and lends itself for use in craft or vehicles where space is at a premium. The device is reliable in performance, and cannot get out of order during normal usage thereof, except for failure of the lamp which would be detected by the pilot light arrangement.

45 As various changes may be made in the form, construction and arrangement of the parts herein, without departing from the spirit and scope of the invention and without sacrificing any of its advantages, it is to be understood that all matter herein is to be interpreted as illustrative and not in any limiting sense.

60 I claim:

1. In apparatus for detecting suspended matter in a fluid, the combination of a casing having an upper wall and having a front wall adapted to constitute a portion of an instrument panel and being provided with a sight opening, said casing having a window extending from about the lower edge of said opening inwardly into said casing in a generally longitudinal direction with respect to said casing, a light source in said casing for providing a beam of light, means for directing the light beam towards the inner side of said front wall in a direction substantially parallel to said window, opaque baffle means in said casing in the line of vision between said opening and said light beam directing means,

and means for circulating a stream of fluid in which suspended matter is to be detected through said casing and through the light beam adjacent said window.

2. In apparatus for detecting suspended matter in a fluid, the combination of a casing having an upper wall and having a front wall adapted to constitute a portion of an instrument panel and being provided with a sight opening, said casing having a window extending from about the lower edge of said opening inwardly into said casing in a generally longitudinal direction with respect to said casing and having an opaque baffle wall extending from said window adjacent its inner end to said upper wall, a light source in said casing rearwardly disposed of said baffle wall for providing a beam of light, means for directing the light beam towards the inner side of said front wall in a direction substantially parallel to said window, and means for circulating a stream of fluid in which suspended matter is to be detected through said casing and through the light beam adjacent said window.

3. In apparatus for detecting suspended matter in a fluid, the combination of a casing having an upper wall and having a front wall adapted to constitute a portion of an instrument panel and being provided with a sight opening, said casing having a window extending from about the lower edge of said opening inwardly into said casing in a generally longitudinal direction with respect to said casing and having an opaque baffle wall extending from said window adjacent its inner end to said upper wall, a partition in said casing having an aperture therein, a light source in said casing rearwardly disposed of said partition for providing a beam of light, means between said light source and said partition for directing the light beam through said partition aperture towards the inner side of said front wall in a direction substantially parallel to said window, and means for circulating a stream of fluid in which suspended matter is to be detected through said casing and through the light beam adjacent said window.

4. In apparatus for detecting suspended matter in a fluid, the combination of a casing having a rear wall and an upper wall and having a front wall adapted to constitute a portion of an instrument panel and being provided with a sight opening, said casing having a window extending from about the lower edge of said opening inwardly into said casing in a generally longitudinal direction with respect to said casing and having an opaque baffle wall extending from said window adjacent its inner end to said upper wall, a partition in said casing having an aperture therein, a light source in said casing rearwardly disposed of said partition for providing a beam of light, means between said light source and said partition for directing the light beam

through said partition aperture towards the inner side of said front wall in a direction substantially parallel to said window, and means for circulating a stream of fluid in which suspended matter is to be detected through said casing and through the light beam adjacent said window, said last mentioned means including an inlet and an outlet in said rear wall and including a conduit in said casing connected to said inlet, and having an opening between said front wall and said partition.

5. In apparatus for detecting suspended matter in a fluid, the combination of a casing having a front wall provided with a sight opening, said casing having a window extending from about the lower edge of said opening inwardly into said casing in a generally longitudinal direction with respect to said casing, translucent means in said wall adjacently below said window, means for circulating a stream of fluid in which suspended matter is to be detected through said casing and through a zone adjacently below said window, a light source in said casing providing a beam of light, means for directing the beam of light substantially parallel to said window and through said zone and directly on said translucent means, a shutter in said casing adapted to be positioned between said translucent means and said light beam directed on said translucent means, and means for operating said shutter from the exterior of said front wall.

6. In apparatus for detecting suspended matter in a fluid, the combination of a casing having an upper wall and having a front wall adapted to constitute a portion of an instrument panel and being provided with a sight opening, said casing having a window extending from about the lower edge of said opening inwardly into said casing in a generally longitudinal direction with respect to said casing, translucent means in said wall adjacently below said window, a light source in said casing for providing a beam of light, means for directing the light beam towards the inner side of said front wall in a direction substantially parallel to said window and directly on said translucent means, opaque baffle means in said casing in the line of vision between said opening and said light beam directing means, and means for circulating a stream of fluid in which suspended matter is to be detected through said casing and through the light beam adjacent said window.
